UNITED STATES PATENT OFFICE.

JOHN BURTON AND WILLIAM B. LODWICK, OF MYSTIC, IOWA.

COAL-MINING MACHINE.

SPECIFICATION forming part of Letters Patent No. 699,864, dated May 13, 1902.

Application filed November 12, 1900. Serial No. 36,317. (No model.)

To all whom it may concern:

Be it known that we, JOHN BURTON and WILLIAM B. LODWICK, citizens of the United States, residing at Mystic, in the county of 5 Appanoose and State of Iowa, have invented a new and useful Coal-Mining Machine, of which the following is a specification.

Our invention has relation to improvements in coal-mining machines; and it consists in the construction and arrangement of parts, as will be hereinafter described, and particularly pointed out in the claim.

In the accompanying drawings, Figure 1 is a top view of our invention. Fig. 2 is an end view. Fig. 3 is a side view. Fig. 4 are views of the cutting-teeth, showing the construction of same. Fig. 5 is a bottom view of the frame, showing the eccentric gear-wheels for operating the drive-shaft.

Referring to the drawings, the letter *e* denotes the framework of our machine, made, preferably, in rectangular form, having journaled in the side bars or rails thereof a shaft *e'*, having on one of its outer ends a drive-wheel *a*. Mounted on the shaft *e'* and adapted to slide thereon are bevel gear-wheels *c* and *b*, spaced at suitable distances apart thereon for a purpose presently to be explained. Secured to the opposite sides of the frame 25 and arranged one above the other are girths *m* and *m'*, having the opposite ends of a vertical worm-shaft *i* journaled therein. The upper end of said shaft passes through an elongated slot in a slide *S*, mounted on said 30 girth *m*, said slide having stops *r*, whereby the bevel gear-wheels *c* or *b* are adapted to alternately engage the bevel gear-wheel *d*. When required, any suitable means may be connected to the slide for operating the same.

To the lower end of the worm-shaft *i* is secured a cog-gear wheel *m'*, (shown in Fig. 1,) which meshes with crank-wheels *f f'*, journaled on stub-shafts *f' f'*, secured to a cross-bar *l'* of the frame, (shown in Figs. 1 and 3,) 45 and each of said wheels is eccentrically pivoted to the drive-shaft *g* at *f² f²'*, as shown in Figs. 1 and 3, whereby a longitudinal vertical movement is imparted to the cutter-bar *J*, which is secured to the drive-shaft *g*, as 50 shown in Fig. 1. The outer or free end of the cutter-bar *J* is curved or rounded and

provided with slots formed in the top and edge surfaces thereof.

The letter *K*, as shown in Fig. 4, represents the teeth of the cutter-bar, each of which is 55 provided with a head *c³*, body portions *c⁴*, and forked ends *c⁵*, the said body portions *c⁴* between the heads *c³* and the ends *c⁵* and provided with cut-away portions *c⁶*, forming shoulders *c⁷*, so that when the teeth are mounted in the slots of the cutter-bar the shoulders *c⁷* will abut against the outer face portions of the cutter-bar, the heads *c³* being secured to the upper face portions thereof by means of bolts *g'* or other suitable fastening 60 65 means.

The letter *H* represents axles journaled in suitable bearings in the bottom side rails of the frame and having rigidly mounted on the ends thereof toothed wheels *h*, which are 70 adapted to travel in the paths of tracks *L*, having teeth *m⁶* corresponding to those of said tracks.

The letter *p* designates a horizontally-arranged worm-shaft journaled at one end in a 75 bearing *p⁴*, the opposite end thereof journaled in a suitable bearing of the frame and said end having thereon a gear-wheel *m⁹*. Mounted on the rear axle is a toothed wheel *p'*, (shown in dotted lines, Fig. 3, and also shown in Fig. 80 2,) which meshes with a worm-shaft *p*, and by shifting the bevel-gear *c* in contact with the bevel-gear *d* by means of the slide *S* the vertical worm-shaft *i* meshes with the toothed wheel *m⁹*, which imparts motion to the worm-shaft *p*, thereby turning the axle *H*, by means 85 of which the toothed wheels *h* engage the teeth of the track and travel therein for the purpose of moving the machine.

In Fig. 1 we show a portion of the teeth 90 connected to the cutter-bar for the purpose of illustration. Those marked in dotted lines indicate the direction each tooth will travel when the cutter-bar is in motion. The tooth marked *x* is the first one to cut, the preceding 95 ones following in line thereafter. The teeth during the cutting process remove the cuttings from under the same and deposit them outward therefrom.

We wish it to be understood that our machine may be driven by any well-known power, preferably by a gasoline-engine.

Having described our invention, what we claim is—

In a coal-mining machine, the combination with the frame having a rotating shaft with 5 sidewise - movable beveled gear - wheels arranged at suitable distances apart thereon, girths arranged one above the other, a slotted slide mounted on the upper girth, a vertical worm-shaft having its upper end journaled in 10 the upper girth and passing through the slot of the slide, a bevel-gear on said upper end of the worm-shaft, a cog gear-wheel on the lower end thereof meshing with crank-wheels journaled on a cross-bar of the frame, a cutter-

bar drive - shaft, a cutter - bar with teeth 15 mounted on the crank-pins of the said crank-wheels, whereby a longitudinal and vertical movement is imparted to said cutter-bar, substantially as specified.

In testimony whereof we have signed our 20 names to this specification in the presence of two witnesses.

JOHN BURTON.
WM. B. LODWICK.
